CLAIM

The ornamental design for a tissue suspension adaptor, as shown and described.

DESCRIPTION

FIG. 1 is a front perspective view of a tissue suspension adaptor showing our new design;

FIG. 2 illustrates a front view of the adaptor of FIG. 1, wherein the back view is a minor image thereof;

FIG. 3 illustrates a right side view of the adaptor of FIG. 1, wherein the left side view is a mirror image thereof;

FIG. 4 illustrates a top view of the adaptor of FIG. 1; and,

FIG. 5 illustrates a bottom view of the adaptor of FIG. 1. The dot-dash broken lines depict a boundary of the claimed design and form no part thereof. The dash-dash broken lines depict portions of the tissue suspension adaptor that form no part of the claimed design.
